UNITED STATES PATENT OFFICE.

GEORGE E. BISHOP, OF CLEVELAND, OHIO.

AUTOMOBILE INCLOSURE.

Application filed March 2, 1923. Serial No. 622,337.

My invention relates to automobile inclosures and particularly to that section of such devices which is mounted upon the automobile door and forms in effect the upper fabric section of the automobile door. My invention is designed to provide such a curtain which shall ride in and out with the door as the latter is opened and closed; and which will have incorporated with it such mounting means and such an assembly of celluloid transparencies that, when not in service, the curtain may be longitudinally folded, or both longitudinally and vertically folded, into a package of that size and shape which answers the particular storage facilities of the user. The ability to thus fold the curtain resides partly in the fact that none of the celluloid transparencies include the longitudinal planes in which adjacent support rod section ends lie when they are released from supporting duty, and also that the free ends of any longitudinal fabric strengthening members do lie in vertical planes passing between adjacent transparencies, all as will hereinafter fully appear in detail. Other advantages of my improved door curtain will appear later in the following detail description as particularly applied to the accompanying drawing.

The annexed drawing and the following description set forth in detail certain means embodying my invention, such disclosed means, however, constituting but a few of the various embodiments in which the principles of my invention may be used.

In said annexed drawing:

Figure 1 represents an inside elevation of one of my improved door curtains;

Figure 2 represents a fragmentary elevation of said curtain when certain parts hereinafter fully described are so positioned as to enable the folding of the curtain into the desired package;

Figure 3 represents an elevation of a modified form of supporting frame, also showing a different arrangement of transparencies;

Figure 4 is a fragmentary elevation showing modified means for supporting the curtain together with a slightly modified form of longitudinal strengthening means; and

Figure 5 represents a fragmentary plan view of an automobile body and door and contiguous curtain frame elements, for the purpose of illustrating how the bottom door section of my supporting rod is so mounted as to make necessary only two turns or bends

in said rod to form a bottom offset portion therein.

In the annexed drawing wherein the same ordinals respectively refer to similar parts in the several views, I indicate curtain fabric by the ordinal 1 with which are incorporated celluloid transparencies 2 of different sizes and shapes and disposed in different positions as fully described and for the purposes hereinafter fully set forth. The fabric 1 is formed with such hems, stitching, etc., as is desirable and particularly with a vertical pocket 3 disposed along the closing edge of the door curtain which overlaps the adjacent side inclosure sections 29, Figure 5. This pocket 3 is for the reception of a supporting member which will be hereinafter fully described. The curtain is adapted to be mounted upon the automobile door 4, Figure 5, by means of a rod which is sub-divided into sections, particularly two sections 5 and 6, as herein shown and described, the lower section 6 being received by the rectangular socket 25 formed in the door 4, by means of an offset portion 7 having a lower supporting end 7' of rectangular cross-section. The supporting rod 5-6 is formed with this offset 7 because the pocket 3 which receives the rod 5-6 is disposed along the closing, lapping edge of the door curtain and the rod 5-6 is mounted upon the door. Means must be provided for securing together the rod sections 5 and 6 to render them relatively rigid transversely of their length when the inclosure is in use and these means take several forms according to my invention, all of the forms being such that these securing means are removable or temporarily put out of commission, whereby the rod sections 5 and 6 can be separated and each folded up with the particular part of the fabric to which it belongs. This folding, of course, if different sizes and shapes of packages are desired, requires considerable latitude to be given to the location, size and shapes of the transparencies 2 and I have illustrated this latitude in several ways in the accompanying drawing. As to the different forms of the securing means, I direct attention to one form shown in Figures 1, 2 and 3, and a second form shown in Figure 4. In Figures 1, 2 and 3, a sleeve 8 is formed with a shoulder 9 intermediate its ends, this sleeve 8 in its upper portion being adapted to receive rod section 5 of $\frac{15}{16}$ -inch diameter, for instance, and in its lower portion to receive

rod section 6 of $\frac{3}{8}$ -inch diameter, for instance, the sleeve 8 normally resting by means of its shoulder 9 upon the rod section 6. In Figure 4 I have illustrated the 5 rod sections 5 and 6 as of the same diameter, the abutting ends of the same being surrounded by a plain sleeve 10 which normally rests upon and is supported by means of a stop 12 secured to the rod section 6.

10 The sleeves 8 and 10 are formed with thin, flat actuating members 13 which extend through and from a vertical slit 14 formed in the pocket 3, this slit 14 being long enough to allow the sleeve to be lifted off from the 15 rod section 6, as illustrated in the case of the sleeve 8 in Figure 2, whereby the rod sections 5 and 6 are disengaged one from the other so that they may be folded up with the fabric and transparencies into a small 20 door pocket package, for instance, in the arrangement shown in Figure 1, or into a narrow, long body package, as illustrated by the arrangement shown in Figure 3, the abutting ends of the sections 5 and 6 being spaced 25 enough not to interfere with the longitudinal folding of the curtain, because a lower slit 14' also is formed in the pocket 3 so that, when the curtain is lifted from the automobile door 4, the section 6 can be dropped a 30 limited amount, as plainly shown in Figure 2. In this connection, I wish particularly to point out that the arrangements shown provide means whereby each section of the supporting rod will stay with its cooperating fabric section and not become disengaged therefrom or confused with rod sections belonging to other fabric sections.

I have shown in several of the figures upper strengthening members for the fabric 1, 40 the same being preferably incorporated within the fabric. In Figure 1 this member takes the form of a divided member 15-16, the same being riveted to the fabric 1, this divided arrangement allowing, of course, for 45 a vertical folding of the curtain, as well as the longitudinal folding hereinbefore described whereby a small door pocket package can be formed. The several members of the divided longitudinal strengthening members 50 are separated in the plane of the vertical space between transparencies contained in the door section of the inclosure, so that it is this door section which can be vertically folded. In Figure 3 I have illustrated an upper 55 strengthening member 17, the same being cylindrical and continuous with the supporting section 5. Furthermore, I have illustrated said member 17 as integral with two supporting sections, 5, one at either end, the whole 60 arrangement showing a two-socket support for the door curtain. In Figure 4 I have shown a flat strengthening rod 18 riveted, welded or otherwise suitably secured to the rod section 5.

65 I show my improved door curtain formed

with valance elements 19 and 20 which are adapted to be buttoned to the automobile canopy and also fastened to one lateral edge of the door section proper of the curtain, these valance elements being shown, described and claimed particularly in my U. S. Patent No. 1,244,692. By means of fasteners 21 the curtain is buttoned to the automobile body 4' and by means of fasteners 22 it is buttoned to the door 4. In the case of the 70 double-socket support shown in Figure 3, the left-hand fastener element 21 is also secured to the automobile door 4. The strengthening members and button elements mentioned 75 serve to hold the inclosure longitudinally 80 taut.

I have provided an arrangement of the socket 25 whereby the supporting rod can be formed with the offset 7 and yet it is necessary only to make two turns or bends in the 85 rod. This is accomplished by the means shown particularly in Figure 5 wherein I disclose the socket 25 rectangular in cross-section adapted to receive the section 7' of the supporting rod, a cover or finish plate 90 being indicated by the ordinal 24. It will be noted in this figure that the walls of the socket 25 are set at an angle to the lines of the body 4' and the edges of the door 4 so that section 7' of the offset 7 passes in a 95 straight line, and diagonally of the door 4, from the point 7³, Figure 4, vertically above the socket 25, to the point 7⁴ in the line of the rod sections 5 and 6, or in other words, lies in the plane passing through the axes of the 100 socket and the main body of the rod. Thus, I have only two bends in the supporting member, viz, at the sections 7³ and 7⁴. It will be plainly noted in Figure 5 that the lower 105 part of the socket 25 which receives the rectangular section 7' of the supporting rod is set at the proper angle to take said rod section 7' so as to require only two bends in the supporting member, the result being that by so setting the socket of rectangular cross-section in the door 4, the rods with the offset 7 will serve both as rights and lefts without the necessity of furnishing two designs of 110 rods for this purpose. When these sockets with a rectangular section for preventing turning of the supporting rod are set in the door so as to dispose the walls of the same parallel and at right angles, respectively, to the lines of the body 4', it is necessary to provide both right and left hand designs of 115 rods.

What I claim is:

1. An automobile inclosure comprising, 125 suitable curtain fabric provided with spaced transparencies; a multiple-section rod adapted removably to support the fabric upon the automobile body; means for holding the fabric longitudinally taut; a vertical pocket formed in the fabric and within which the supporting rod is disposed; at least one of 130

- said rod sections being longitudinally adjustable in said pocket in the inoperative position of the supporting rod, and a sleeve surrounding the adjacent rod section ends 5 and normally holding the rod sections relatively rigid transversely of their length, one of the abutting rod sections being formed with means adapted to hold the sleeve in its operative position, said fabric being formed 10 with a vertical slit, and said sleeve being formed with a fingerpiece extending through said slit, whereby the sleeve may be vertically, manually adjusted to release the abutting rod section ends one from the other, 15 none of said transparencies including the longitudinal planes in which the adjacent rod section ends lie when they are released, whereby the inclosure may be folded along longitudinal lines without removing the respective rod sections from the fabric. 20
2. An automobile inclosure comprising, suitable curtain fabric provided with spaced transparencies; a two-section rod adapted removably to support the fabric upon the 25 automobile body; transversely spaced longitudinal strengthening members for holding the door-section of the fabric longitudinally taut; a vertical pocket formed in the fabric and within which the supporting rod is disposed, at least one of said rod sections being longitudinally adjustable in said pocket in the inoperative position of the supporting rod, and a sleeve closely surrounding the adjacent rod section ends and normally holding the rod sections relatively rigid transversely of their length, the upper of said rod sections being of smaller diameter at its abutting end than the diameter of the abutting end of the lower rod section, whereby 30 the latter is formed with a shoulder retaining said sleeve in its operative position, said fabric pocket being formed with a vertical slit, and said sleeve being formed with a finger-piece extending through said slit, whereby the sleeve may be vertically manually adjusted to release the abutting rod section ends one from the other, none of said 35 transparencies including the longitudinal 40 planes in which the adjacent ends of the rod sections lie when they are released, and abutting ends of said strengthening members lying in vertical planes passing between adjacent transparencies, whereby the inclosure may be folded into a storage package along both longitudinal and vertical lines. 45
3. An automobile inclosure comprising, suitable curtain fabric provided with spaced transparencies; a two-section rod adapted removably to support the fabric upon the 50 automobile door, the lower supporting section of said rod being formed with a lateral door section offset; means for holding the fabric longitudinally taut, including a longitudinal strengthening member; a vertical pocket formed in the fabric and within 55 which the vertical sections of the supporting rod are disposed; and a sleeve surrounding the adjacent rod section ends and normally holding the rod sections relatively rigid transversely of their length, one of the abutting 60 rod sections being formed with means adapted to hold the sleeve in its operative position, said fabric pocket being formed with a pair of vertical slits, one of said slits being contiguous to said sleeve, the latter 65 being formed with a projecting finger-piece extending through said slit, whereby the sleeve may be vertically manually adjusted to release the abutting rod section ends one from the other, the second pocket slit being 70 contiguous to said door section offset of the rod, said offset projecting through and being vertically movable in said slit, whereby the abutting rod section ends may be spaced 75 to allow for fabric folding, when the inclosure is removed from the door, none of said transparencies including the longitudinal 80 planes in which the adjacent rod section ends lie when they are released, whereby the inclosure may be folded along longitudinal 85 lines without removing the respective rod sections from the fabric. 90

Signed by me this 24th day of January, 1928.

GEORGE E. BISHOP.
